UNITED STATES PATENT OFFICE

168,632

CARRYING CASE

Erdick H. Nelson, Naperville, Ill.

Application September 15, 1952, Serial No. 21,461

Term of patent 14 years

(Cl. D87—6)

To all whom it may concern:

Be it known that I, Erdick H. Nelson, a citizen of the United States, residing at Naperville, Du Page County, Illinois, have invented a new, original, and ornamental Design for Carrying Case, of which the following is a specification, reference being had to the accompanying drawing, forming a part thereof, in which:

Fig. 1 is a perspective view of a carrying case embodying my new design;

Fig. 2 is a top plan view of the carrying case shown in Fig. 1;

Fig. 3 is a side elevational view thereof, the opposite side being the same as that illustrated; and

Fig. 4 is an end elevational view of the carrying case, the opposite end being the same as that illustrated.

I claim:

The ornamental design for a carrying case, substantially as shown and described.

ERDICK H. NELSON.
